AUTOGRAPHIC REGISTER

John H. Yancey, Sturgis, Mich., assignor to National Carbon Coated Paper Company, Sturgis, Mich.

Application October 26, 1936, Serial No. 107,645

21 Claims. (Cl. 271—2.5)

The main objects of this invention are:

First, to provide in an autographic register of the pull-out type an improved pull-out means which is very easily operated and which has an effective grip on the stationery or record strips and is effective in keeping a plurality of record strips in properly aligned relation.

Second, to provide in an autographic register of this type provided with strip engaging jaws, an improved means for automatically closing the jaws upon the return of the carriage to its initial position and automatically opening them at a predetermined point in its forward stroke.

Third, to provide a structure of this character with means whereby the jaws may be manually closed at an intermediate point in the structure thereof.

Fourth, to provide in an autographic register of the pull-out type a structure which is very compact and one in which the carriage housing constitutes a handle or grip for manipulation of the carriage.

Objects relating to details and economies of the invention will appear from the description to follow. The invention is defined and pointed out in the claims.

A preferred embodiment of the invention is illustrated in the accompanying drawings, in which:

Fig. 1 is a plan view of an autographic register embodying the features of my invention, parts being broken away and sectioned for convenience in illustration.

Fig. 2 is a perspective view.

Fig. 3 is a perspective view with the cover and writing table or platen swung to open position, also illustrating the carbon paper in a preliminary position for interleaving with the record strips.

Fig. 4 is a longitudinal section on line 4—4 of Figs. 1, 10 and 11.

Fig. 5 is an enlarged detail view partially in transverse section on line 5—5 of Fig. 4.

Fig. 6 is an enlarged fragmentary view sectioned on line 6—6 of Figs. 1, 5 and 8.

Fig. 7 is an enlarged detail section on line 7—7 of Fig. 1.

Fig. 8 is an enlarged detail view partially in section on line 8—8 of Fig. 6.

Fig. 9 is a detail section on line 9—9 of Fig. 5.

Fig. 10 is a fragmentary transverse section on line 10—10 of Fig. 1, illustrating the relation of the carbon holder to other parts.

Fig. 11 is a fragmentary horizontal section on line 11—11 of Fig. 12 showing details of the carriage latch or locking mechanism.

Fig. 12 is an enlarged detail view on a line corresponding to line 12—12 of Fig. 11.

Fig. 13 is a fragmentary perspective view showing details of the latch keeper.

In the embodiment of my invention illustrated, the casing 1 is of box-like form and has transverse partitions 2 and 3 providing a rear compartment 4 adapted to receive the stationery supply indicated at 5 and a front compartment 6 adapted to receive a record strip indicated at 7.

In the embodiment illustrated, the stationery comprises three strips, one of the strips being the record strip and the other two strips being torn off into slips as is customary in autographic registers. Above the stationery storage chamber is a tablet or writing table 8 adapted to support the strips to permit entries being made thereon. At one side of this supply chamber is a chamber or chamber-like holder 9 for carbon paper 10, this carbon paper comprising a plurality of strips folded into the packet 11—see Fig. 10.

The cover 12 is hinged at 13 to be closed over the platen or table 8 and has an opening 14 through which the record strips are exposed, as shown in Fig. 1, the record strips being preferably provided with suitable forms in series. The cover is retained in closed position by the latches 15 and 16 pivotally mounted on the top plate 17 which is in substantially the plane of and constitutes a cover or top for the record strip chamber 6. This top plate 17 is provided with a pair of longitudinal slots 18 and has on its underside spaced record strip supporting guides 19, as best shown in Fig. 5.

The rear end of the table 8 is directed downwardly at 20 and a weighted member 21 pivoted at 22 is provided in opposed relation to this down-turned end 21 to apply friction to the record strips, holding them against buckling or looping action on the table. A cross rod 23 is provided to separate and guide the strips to these opposed parts 20 and 21.

On the inner side of the walls of the casing, I mount a pair of slideways 24 and 25 for slidably supporting the pull-out carriage which comprises a cross member 26 having a downwardly facing channel-shaped slide 27 of considerable length embracing the slideway 24, the other end of this cross member being slidably supported by the slideway 25. The slide 27 is braced by the brace 28 so that it does not bind as the carriage reciprocates.

Above the top plate is a carriage housing 29 of general downwardly facing channel-cross section preferably formed as a sheet metal stamping, this

being provided with end members 30 provided with inwardly projecting brackets 31 secured to the ends of the cross bar portion 26 of the carriage. The side walls of the casing are provided with 5 longitudinal slots or recesses 32 receiving these brackets and permitting the reciprocation of the carriage.

On the end members of the carriage I journal rockshafts 33 and 34, the upper rockshaft being 10 above the top plate and the lower rockshaft below the top plate. On these rockshafts I mount jaw members 35 having opposed jaws 36 adapted to open and close by the rocking of the rockshafts. The rockshafts are connected by the 15 toothed segments 37 so that they rock in opposite directions to simultaneously open and close. A coiled spring 38 having one end 39 in supporting engagement with the cross member and its other end 40 in engagement with the lower jaw member 20 acts to urge the jaws to open position.

Means are provided for automatically closing the jaws into clamping engagement with the record strips when the carriage is returned to its initial position and for automatically releasing it 25 when it reaches the limit of its forward stroke or a predetermined point of its stroke. The jaws are shown in closed position in Fig. 6, the record strips being omitted, and in open position in Fig. 7. They are shown in closed position upon the 30 record strips in Figs. 4 and 5. This automatic closing, in the embodiment illustrated, is effected by the reciprocation of the carriage.

The lower rockshaft 34 is provided with a forwardly projecting arm 41 operatively associated 35 with the pivoted dog 42, the dog being pivoted at 43 on the carriage and provided with a nose portion 44 coacting with the arm and a tail portion 45 which is engaged by the actuating means when the carriage is returned to its initial position. A 40 stop pin 46 coacting with spaced stops 47 on this dog limits the swinging movement of the dog. When the dog is in engaged position, its point of engagement with the lever is at the rear of its pivot axis so that the tension of the jaw opening 45 spring coacting with the dog holds the parts in locking position, as shown by full lines in Fig. 6 and by dotted lines in Fig. 7.

The actuating means consists of the actuating arm 48 which is pivoted at 49 and provided with 50 an actuating spring 50, one arm of which is selectively engageable with one of the holes 51 in the segment 52, thus enabling the adjustment or 55 tension of the spring which is coiled about the pivot for the arm, as shown in Fig. 8, the other end of the spring engaging the actuating arm. An adjustable stop or bumper 53 is provided for the actuating arm.

The carriage is provided with a tappet 54 which 60 on the rearward stroke of the carriage engages the escapement member 55 of the actuating arm, this escapement member being pivoted at 56 and being supported by the lug 57 on the rearward stroke of the carriage or on the rearward stroke 65 of the arm as it is propelled by the carriage against the tension of its actuating spring, the escapement member, however, yielding on the forward stroke of the carriage to permit the passage of the tappet, the escapement member being held 70 yieldingly in position against the stop 57 by the spring 58.

With this arrangement of parts, as the carriage is returned to its initial position, the actuating arm is forced rearwardly by the carriage until the tappet passes over the top of the escape-

ment member 55 when the spring swings or actuates the arm, carrying the lug 59 projecting from the side thereof against the tail of the dog and swinging the dog to its jaw actuating and locking position as shown by full lines in Fig. 6. As the carriage is moved forwardly, the jaw actuating and holding dog is brought into engagement with the adjustable trip 60 and swung to released position shown by full lines in Fig. 7, or until it snaps out from under the jaw arm 41.

To permit the closing of the jaws at an intermediate point in the reciprocation of the carriage, I provide the dog 42 with a laterally projecting pin 61 which terminates in the finger piece 62 at the outside of the casing, the pin projecting 15 through one of the slots.

With this arrangement, after the jaws have been opened by the trip means described and retracted sufficiently to allow the swinging of the dog, the dog may be actuated manually to engage the jaws. It may be desired to pull out a portion of a record strip in adjustment or for other manipulations, making it possible for the feeding of any length desired less than the maximum although it is intended that in ordinary 25 practice when adjusted, the carriage shall normally be reciprocated to feed predetermined lengths and the manual manipulation of the jaws is unnecessary.

After the strips have been fed, the delivered 30 record may be severed against the shear bar 63 provided for the purpose in the lower edge of the front wall of the housing.

To prevent accidental actuation of the carriage as might occur by a customer, for example, idly 35 fingering the machine or the carriage being actuated by accidentally brushing against it, I provide an automatic locking or latching means for retaining it in its retracted position. In the embodiment illustrated, this comprises a lever-like 40 latch 65 which is pivoted at 66 on the rear wall 45 of the carriage housing (see Figs. 10 and 11) and is yieldingly urged into engaging position by means of the coiled spring 67.

The keeper 68 is, in the embodiment illustrated, 45 formed upon the latch or button 15 provided for holding the cover in its closed position. The forward part of this keeper is rounded at 69 so that the latch readily slides over and drops down behind the shoulder of the keeper. To release the 50 latch, I provide a bar-like finger piece 70 which is supported by a spring 71 mounted on the inner 55 side of the rear wall of the carriage housing, this finger piece having a beveled or inclined portion 72 coacting with a beveled edge 73 on the latch lever 65—see Fig. 12. This finger piece is so positioned that when the operator grasps the housing of the carriage which, as stated, is designed to serve as a hand piece for the manipulation of 60 the carriage, the finger piece may be released.

Structures embodying the features of my invention are very simple, convenient to use, and the operation is entirely automatic—that is, it is only necessary for the operator to grasp the carriage to actuate the jaws and feed the record strips.

I have illustrated and described my improvements in embodiments which I have found very practical. I have not attempted to illustrate certain embodiments or adaptations which I contemplate as it is believed that this disclosure will enable those skilled in the art to embody or adapt my improvements as may be desired.

Having thus described my invention, what I

claim as new and desire to secure by Letters Patent is:

1. In an autographic register, the combination of a casing provided with a top plate at its front end having spaced longitudinal slots, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, rockshafts journaled in said end members of said housing, the upper rockshaft being disposed above the top plate and the lower below the top plate, opposed jaw members on said rockshaft provided with spaced jaws aligned with said slots in said top plate, connections for said rockshafts whereby they are simultaneously operated in opposite directions, a coiled spring on the lower rockshaft engaging the lower jaw member and acting to urge said jaw members to open position, an arm on said lower rockshaft, a jaw actuating and holding dog pivotally mounted on said carriage to coact with said arm for actuating said jaws to engaging position and for holding them in engaged position during the forward stroke of the carriage, an adjustable tripping member for releasing said dog at the end of the forward stroke of the carriage, a tappet on said carriage, and a pivotally mounted actuating arm provided with an actuating spring and positioned in the path of said tappet on said carriage and provided with a laterally projecting lug coacting with said dog for swinging it to jaw actuating position, said arm being provided with a spring supported pivoted tappet engaging escapement member yielding on the forward stroke of the carriage to permit the passage of the tappet, said tappet releasing the escapement member when the carriage is returned to its initial position.
2. In an autographic register, the combination of a casing provided with a top plate at its front end having spaced longitudinal slots, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, rockshafts journaled in said end members of said housing, the upper rockshaft being disposed above the top plate and the lower below the top plate, opposed jaw members on said rockshaft provided with spaced jaws aligned with said slots in said top plate, connections for said rockshafts whereby they are simultaneously operated in opposite directions, a coiled spring on the lower rockshaft engaging the lower jaw member and acting to urge said jaw members to open position, an arm on said lower rockshaft, a jaw actuating and holding dog pivotally mounted on said carriage to coact with said arm for actuating said jaws to engaging position and for holding them in engaged position during the forward stroke of the carriage, a tappet on said carriage, and a pivotally mounted actuating arm provided with an actuating spring and positioned in the path of said tappet on said carriage and provided with a laterally projecting lug coacting with said dog for swinging it to jaw actuating position, said arm being provided with a spring supported pivoted tappet engaging escapement member yielding on the forward stroke of the carriage to permit the passage of the tappet, said tappet releasing the escapement member when the carriage is returned to its initial position.

said tappet releasing the escapement member when the carriage is returned to its initial position.

3. In an autographic register, the combination of a casing provided with a top plate at its front end having spaced longitudinal slots, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, rockshafts journaled in said end members of said housing, the upper rockshaft being disposed above the top plate and the lower below the top plate, opposed jaw members on said rockshaft provided with spaced jaws aligned with said slots in said top plate, connections for said rockshafts whereby they are simultaneously operated in opposite directions, means acting to urge said jaw members to open position, an arm on said lower rockshaft, a jaw actuating and holding dog pivotally mounted on said carriage to coact with said arm for actuating said jaws to engaging position and for holding them in engaged position during the forward stroke of the carriage, an adjustable tripping member for releasing said dog at the end of the forward stroke of the carriage, a tappet on said carriage, and a pivotally mounted actuating arm provided with an actuating spring and positioned in the path of said tappet on said carriage and provided with a laterally projecting lug coacting with said dog for swinging it to jaw actuating position, said arm being provided with a spring supported pivoted tappet engaging escapement member yielding on the forward stroke of the carriage to permit the passage of the tappet, said tappet releasing the escapement member when the carriage is returned to its initial position.
4. In an autographic register, the combination of a casing provided with a top plate at its front end having spaced longitudinal slots, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, rockshafts journaled in said end members of said housing, the upper rockshaft being disposed above the top plate and the lower below the top plate, opposed jaw members on said rockshaft provided with spaced jaws aligned with said slots in said top plate, connections for said rockshafts whereby they are simultaneously operated in opposite directions, means acting to urge said jaw members to open position, an arm on said lower rockshaft, a jaw actuating and holding dog pivotally mounted on said carriage to coact with said arm for actuating said jaws to engaging position and for holding them in engaged position during the forward stroke of the carriage, a tappet on said carriage, and a pivotally mounted actuating arm provided with an actuating spring and positioned in the path of said tappet on said carriage and provided with a laterally projecting lug coacting with said dog for swinging it to jaw actuating position, said arm being provided with a spring supported pivoted tappet engaging escapement member yielding on the forward stroke of the carriage to permit the passage of the tappet, said tappet releasing the escapement member when the carriage is returned to its initial position.

5. In an autographic register, the combination of a casing provided with a longitudinally slotted top plate, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, 5 mounted within said casing in a plane below said side slots, a reciprocating carriage slideable on said slideways, a carriage housing disposed transversely above said top plate and provided with end members mounted on said carriage, 10 rockshafts journaled in said end members of said housing with one above and the other below the top plate, opposed jaws on said rockshafts, connections for said rockshafts whereby they are simultaneously operated in opposite directions, a 15 spring acting to urge said jaws to open position, an arm on one of said rockshafts, a jaw actuating and holding dog pivotally mounted on said carriage to coact with said arm for actuating said jaws to engaging position and for holding them in 20 engaged position during the forward stroke of the carriage, a tappet on said carriage, and a spring actuated pivotally mounted actuating arm positioned in the path of said tappet on said carriage and provided with a laterally projecting lug 25 coacting with said dog for swinging it to jaw actuating position, said arm being provided with a pivoted tappet engaging escapement member yielding on the forward stroke of the carriage to permit the passage of the tappet, said tappet 30 releasing the escapement member when the carriage is returned to its initial position.

6. In an autographic register, the combination of a casing provided with a longitudinally slotted top plate, the side walls of the casing below said top plate being longitudinally slotted, slideways mounted within said casing in a plane below said side slots, a reciprocating carriage slideable on said slideways, a carriage housing disposed transversely above said top plate and provided with end members mounted on said carriage, rockshafts 35 journaled in said end members of said housing with one above and the other below the top plate, opposed jaws on said rockshafts, connections for said rockshafts whereby they are simultaneously operated in opposite directions, a spring acting to urge said jaws to open position, an arm on one of said rockshafts, a jaw actuating and holding dog pivotally mounted on said carriage to coact with 40 said arm for actuating said jaws to engaging position and for holding them in engaged position during the forward stroke of the carriage, and a spring actuated member for actuating said dog on the return stroke of the carriage. 45

7. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts 50 in opposite directions to open and close the jaws, an arm on one of said rockshafts, a jaw actuating and holding dog pivotally mounted on said carriage to coact with said arm for actuating said jaws to engaging position and for holding them in engaged position during the forward stroke of the carriage, a tripping member for releasing said dog at the end of the forward stroke of the carriage, a tappet on said carriage, and a spring 55 actuated pivotally mounted actuating arm positioned in the path of said tappet on said carriage and provided with a laterally projecting lug coacting with said dog for swinging it to jaw actuating position, said arm being provided with a pivoted tappet engaging escapement member 60

yielding on the forward stroke of the carriage to permit the passage of the tappet, said tappet releasing the escapement member when the carriage is returned to its initial position.

8. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts in opposite directions to open and close the jaws, an arm on one of said rockshafts, a jaw actuating and holding dog pivotally mounted on said carriage to coact with said arm for actuating said jaws to engaging position and for holding them in engaged position during the forward stroke of the carriage, and a spring actuated pivotally mounted actuating arm positioned in the path of said tappet on said carriage and provided with a laterally projecting lug coacting with said dog for swinging it to jaw actuating position, said arm being provided with a pivoted tappet engaging escapement member yielding on the forward stroke of the carriage to permit the passage of the tappet, said tappet releasing the escapement member when the carriage is returned to its initial position. 20

9. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts in opposite directions to open and close the jaws, an arm on one of said rockshafts, a jaw actuating and holding dog mounted on said carriage to coact with said arm for actuating said jaws to engaging position and for holding them in engaged position during the forward stroke of the carriage, a tripping member for releasing said dog at the end of the forward stroke of the carriage, and a spring actuated actuating member for said dog to be actuated by said carriage on the return stroke of the carriage. 30

10. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts in opposite directions to open and close the jaws, an arm on one of said rockshafts, a jaw actuating and holding dog mounted on said carriage to coact with said arm for actuating said jaws to engaging position and for holding them in engaged position during the forward stroke of the carriage, a tripping member for releasing said dog at the end of the forward stroke of the carriage, and a spring actuated actuating member for said dog to be actuated by said carriage on the return stroke of the carriage. 40

11. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts in opposite directions to open and close the jaws, a spring acting to urge said jaws to open position, means on said carriage for holding said jaws in closed position, means for automatically actuating said jaws to closed position when the carriage is returned to its initial position, and adjustable 50

means for automatically releasing said jaws at a predetermined point in the forward stroke of the carriage.

12. In an autographic register, the combination of a casing provided with a longitudinally slotted top plate, a reciprocating carriage, rockshafts journaled on said carriage on opposite sides of said top plate, coacting jaws on said rockshafts engaging through said slot in said top plate, means for simultaneously rocking said rockshafts in opposite directions to open and close the jaws, means on said carriage for holding said jaws in closed position, and means for automatically actuating said jaws to closed position when the carriage is returned to its initial position.

13. A paper feed for autographic registers, comprising a reciprocating carriage, rockshafts journaled on said carriage, coacting opposed jaws on said rockshafts, means for simultaneously rocking said rockshafts in opposite directions to open and close the jaws, a spring acting to urge said jaws to open position, means on said carriage for holding said jaws in closed position, means for actuating said holding means to move said jaws to closed position when the carriage is returned to its initial position, and means for actuating said holding means to release said jaws at a predetermined point in the forward stroke of the carriage.

14. A paper feed for autographic registers, comprising a reciprocating carriage, rockshafts journaled on said carriage, coacting opposed jaws on said rockshafts, means for simultaneously rocking said rockshafts in opposite directions to open and close the jaws, a spring acting to urge said jaws to open position, means on said carriage for holding said jaws in closed position, and means for actuating said holding means to move said jaws to closed position when the carriage is returned to its initial position.

40 15. A paper feed for autographic registers, comprising a reciprocating carriage, rockshafts journaled on said carriage, coacting opposed jaws on said rockshafts, means for simultaneously rocking said rockshafts in opposite directions to open and close the jaws, means on said carriage for holding said jaws in closed position, means for actuating said holding means to move said jaws to closed position when the carriage is returned to its initial position, and means for actuating said holding means to release said jaws at a predetermined point in the forward stroke of the carriage.

16. In an autographic register, the combination with a casing provided with a longitudinally slotted top plate, of a reciprocating carriage provided with a housing adapted as a hand-hold, rockshafts journaled on said carriage and provided with opposed coacting jaws, means for simultaneously rocking said rockshafts in opposite directions to open and close the jaws, means for automatically engaging the jaws when the carriage is returned to its initial position, means for automatically releasing the jaws at a predetermined point in the forward stroke of the carriage, and a finger piece operatively associated with the jaws whereby they may be manually closed at an intermediate point on the return stroke of the carriage.

70 17. In an autographic register, the combination with a casing provided with a longitudinally slotted top plate, of a reciprocating carriage provided with a housing adapted as a hand-hold, rockshafts journaled on said carriage and provided with opposed coacting jaws, means for simultaneously rocking said rockshafts in opposite directions to open and close the jaws, means for

automatically engaging the jaws when the carriage is returned to its initial position, and a finger piece operatively associated with the jaws whereby they may be manually closed at an intermediate point on the return stroke of the carriage. 5

18. In an autographic register, the combination with a casing provided with a longitudinally slotted top plate, of a reciprocating carriage provided with a housing adapted as a hand-hold, 10 rockshafts journaled on said carriage and provided with opposed coacting jaws, means for simultaneously rocking said rockshafts in opposite directions to open and close the jaws, means for automatically engaging the jaws when the carriage is returned to its initial position, means for automatically releasing the jaws at a predetermined point in the forward stroke of the carriage, a finger piece operatively associated with the jaws whereby they may be manually closed at 15 an intermediate point on the return stroke of the carriage, a spring actuated lever-like latch pivotally mounted in said housing, a keeper with which said latch automatically engages when the carriage is returned to its initial position, and a finger piece on the rear side of said housing operatively associated with said latch and positioned so that it may be actuated by the hand grasping the housing for the reciprocation of the carriage. 20

30 19. In an autographic register, the combination with a casing provided with a longitudinally slotted top plate, of a reciprocating carriage provided with a housing adapted as a hand-hold, rockshafts journaled on said carriage and provided with opposed coacting jaws, means for simultaneously rocking said rockshafts in opposite directions to open and close the jaws, means for automatically engaging the jaws when the carriage is returned to its initial position, means for automatically releasing the jaws at a predetermined point in the forward stroke of the carriage, a spring actuated lever-like latch pivotally mounted in said housing, a keeper with which said latch automatically engages when the carriage is returned to its initial position, and a finger piece on the rear side of said housing operatively associated with said latch and positioned so that it may be actuated by the hand grasping the housing for the reciprocation of the carriage. 35

45 20. In an autographic register, the combination with a casing provided with a longitudinally slotted top plate, of a reciprocating carriage provided with a housing adapted as a hand-hold, rockshafts journaled on said carriage and provided with opposed coacting jaws, means for simultaneously rocking said rockshafts in opposite directions to open and close the jaws, means for automatically engaging the jaws when the carriage is returned to its initial position, means for automatically releasing the jaws at a predetermined point in the forward stroke of the carriage, a finger piece operatively associated with the jaws whereby they may be manually closed at an intermediate point on the return stroke of the carriage, a latch on said carriage, a keeper with which said latch automatically engages when the carriage is returned to its initial position, and a finger piece on said housing operatively associated with said latch and positioned so that it may be actuated by the hand grasping the housing for the reciprocation of the carriage. 50

55 21. In an autographic register, the combination with a casing provided with a longitudinally slotted top plate, of a reciprocating carriage pro- 70

vided with a housing adapted as a hand-hold, rockshafts journaled on said carriage and provided with opposed coacting jaws, means for simultaneously rocking said rockshafts in opposite directions to open and close the jaws, means for automatically engaging the jaws when the carriage is returned to its initial position, means for automatically releasing the jaws at a predetermined point in the forward stroke of the car-

riage, a latch on said carriage, a keeper with which said latch automatically engages when the carriage is returned to its initial position, and a finger piece on said housing operatively associated with said latch and positioned so that it may be actuated by the hand grasping the housing for the reciprocation of the carriage. 5

JOHN H. YANCEY.
